UNITED STATES PATENT OFFICE.

WILLIAM T. COGGESHALL, OF LOWELL, MASSACHUSETTS.

LOOM-SHUTTLE SPINDLE.

SPECIFICATION forming part of Letters Patent No. 323,115, dated July 28, 1885.

Application filed February 15, 1883. Renewed December 26, 1884. (No model.) Patented in England March 6, 1883, No. 1,194; in France March 6, 1883, No. 154,111, and in Belgium March 6, 1883, No. 60,663.

To all whom it may concern:

Be it known that I, WILLIAM T. COGGESHALL, a citizen of the United States, residing at Lowell, in the county of Middlesex and State 5 of Massachusetts, have invented certain new and useful Improvements in Loom-Shuttle Spindles; and I do declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Figure 1 of the drawings is a top view of the spindle. Fig. 2 is a bottom view of the same. Fig. 3 is a central vertical longitudinal section.

This invention has relation to cop-retaining 20 spindles for loom-shuttles; and it consists in the construction and novel arrangement of parts, as will be hereinafter fully described, and particularly pointed out in the claims appended.

25 In the accompanying drawings, the letter *a* designates the spindle of a loom-shuttle, having a longitudinal groove or slot, *b*; or, preferably, a groove is made from the heel portion forward, and near the front end of the 30 spindle a slot is made through the bottom of the groove, as indicated at *c*.

d represents a spring of elongated form, flattened from side to side. This spring is made with its upper edge, *e*, somewhat concave or 35 inclined from the middle portion upward toward each end. The upper edge of the spring is usually serrated, the abrupt ends of the teeth being toward the heel. The spring is fastened into the groove or slot by its middle

40 portion in a rigid manner, the fastening being accomplished by means of two transverse rivets, *g g*, or by means of solder; or the middle portion of the spring may be driven into a tight seat formed in the grooved portion of

45 the spindle to receive it, or any ordinary means of rigidly fastening the spring at its middle portion may be employed. If solder is used, the side walls of both slot and spring, or of either of them, may be notched or re- 50 cessed to afford a hold to the solder. The spring thus fastened to the spindle provides a

rear spring-branch, *h*, having an upward bend, and a front spring-branch, *k*, having an upward bend, the upper edges of both branches projecting upward out of the groove or slot. In this 55 manner a heel-spring, *h*, is provided, as well as a front spring, *k*, so that when the cop is put on it is held in rear as well as in front. As the thread is unwound from the cop its resistance to the front end of the spring is 60 lessened. At the heel portion, however, the full resistance of the cop is maintained against 65 the heel of the spring until the thread has been almost entirely unwound. The cop when first put on receives a constant pressure in its 70 interior from the spring, such pressure being greatest at the extreme points. The thread unwinds from the point of the cop, and as the resistance of the thread gradually lessens at this point the spring gradually rises and still 75 holds the cop in place. The full body of the thread at and near the heel of the spindle is unwound lastly, and the heel-spring operates in such relation to this portion that the cop is prevented from slipping, and the consequent breaking of the cop is avoided, as it is held at both the point and the heel. This 80 double-acting spring is designed to prevent waste, as it will effectually hold the cop on the spindle until all the thread has been unwound 85 therefrom. In some cases it is desirable to provide deep serrations in the upper edge of this spring, and in order to afford them full play in engaging the cop, depressions *l* are formed in the top of the spindle on each side 90 of the spring.

The spring is designed, usually, to be formed with a lug or projection, *z*, at its rear end, which serves to prevent the cop from being pressed too far back on the spindle.

Having described this invention, what I claim, and desire to secure by Letters Patent, is—

1. A longitudinally grooved or slotted spindle having a spring rigidly fastened at its 95 middle portion in the groove of the spindle, with its upper edge projecting out of the slot in rear and in front of the fastened portion, substantially as specified.

2. The combination of the cop-holding 100 spring *d*, having a concave upper edge, serrated, as shown, with a longitudinally-grooved

spindle, *a*, in which it is rigidly fastened at its middle portion, substantially as specified.

3. The combination, with a shuttle-spindle, *a*, of a flat *cop*-holding spring having a serrated concave upper edge, and fastened rigidly at its middle portion within the longitudinal groove of said spindle, the spindle *a* being provided with depressions *l* in its top on each side of the groove to afford full play to the serrations in the spring, substantially as specified.

4. The combination, with a longitudinally-grooved spindle, of a flat spring having a ser-

rated concave upper edge, and seated edge-wise in the groove, and fastened rigidly therein at its middle portion, said spring being free at its ends and having its rear end provided with a stop-projection, *z*, substantially as specified. 15

In testimony whereof I affix my signature 20 in presence of two witnesses.

WILLIAM T. COGGESHALL.
